Attleboro,

UNITED STATES PATENT OFFICE

VICTOR VAN DER LINDE, OF TUCKAHOE, NEW YORK, ASSIGNOR TO FINE ART FOODS,
INCORPORATED, OF TUCKAHOE, NEW YORK, A CORPORATION OF DELAWARE

CANISTER

Application filed June 14, 1928. Serial No. 285,489.

This invention relates to canisters, and particularly to canisters of paper stock, and will be readily understood from the following description, in conjunction with the accompanying drawings, in which—

Figure 1 is a perspective view of a canister embodying my invention;

Fig. 2 is a vertical sectional view taken on the line 2 of Fig. 1;

Fig. 3 is a plan view of the canister with the cover removed;

Fig. 4 is a sectional detail, similar to that presented in Fig. 2, illustrating a further modification; and

Fig. 5 is a plan view of the canister with the cover removed, similar to Fig. 3, illustrating a modification.

Referring to the drawings, 10 is the body portion of the canister, which is of frustoconical shape. At an intermediate position, the body portion 10 is provided with a transverse partition 11 which divides it into two compartments 12 and 13. The position of the partition 11 may be varied to meet different requirements, although generally it will be located at a point considerably nearer the upper end, as shown in the drawings.

The body portion 10 and partition 11 are preferably made of stiff waterproofed paper stock, such as waxed paper. Any other suitable material may be used, if desired.

The partition 11 is preferably provided with an upturned flange 14 attached to the body portion 10 by adhesives and extending to the upper edge of the body portion which it greatly stiffens and strengthens, so that a firm seat, and one not easily deformed, is provided for the cover flange.

The larger compartment 13 is filled with coffee, tea, or the like, through the open lower end, after which a waxed cardboard or other type of bottom 15 is inserted and the edge of the body portion is pressed thereover, forming a bead 16 which holds the bottom in place. This insures a hermetically sealed compartment and will preserve the aroma of the contents in its original state for a long period of time.

The upper chamber 12 may be employed to contain a measuring device, samples, instruc-

tions, or other commodities which are to be supplied to the consumer along with the contents of chamber 13. A flanged metallic or paper stock cover 17, which is readily removable, fits over the open top of this chamber and closes the upper end.

The contents of the larger compartment 13 can be conveniently made available for use by removing the cover 17 and the contents of the upper chamber 12 and tearing or cutting out the transverse partition 11. The cover 17 is easily replaced on top of the body portion 10 and preserves the contents of the chamber 13 from dust and exposure.

As shown in Figs. 2 and 3, an outline 18, of weakened material, may be formed in the partition 11 so that a portion of said partition can easily be cut or torn out. This outline preferably comprises a straight edge 19 which can be used to level a measuring spoon.

As shown in Fig. 5, the transverse partition 11 may be provided with a tab 21, made of paper stock, which facilitates the removal of the partition, an outline of which is composed of weakened material and will readily give way when the tab is pulled up. A part of the orifice preferably comprises a straight edge 22 which can be used to level a measuring spoon.

A modification is illustrated in Fig. 4 in which a wire 20 is stretched across the canister below the cover 17 and above the partition 11, to be used in leveling a measuring spoon, the surplus contents falling back into the canister.

While I have shown and described an embodiment of my invention, it is to be understood that it is capable of many modifications. Changes, therefore, in the construction and arrangement may be made which do not depart from the spirit and scope of the invention, as disclosed in the appended claims.

I claim:

1. A canister including a body portion, a readily removable cover, a bottom, and an intermediate partition provided with a tab facilitating the removal of a portion of the partition along an outline of weakened material provided for that purpose, said outline

having a straight edge adapted for leveling a measuring spoon.

2. A canister including a frusto-conical body portion of paper stock adapted for filling through its larger end when inverted and to rest on said larger end, a readily removable metallic cover having a downturned flange fitted to the smaller upper end, a bottom closing the larger end, a bead on the body portion 10 engaging the periphery of the bottom to hold the latter in place, and a transverse partition formed of paper stock and located intermediate the top and bottom of the body portion and marginally in intimate contact with the 15 body portion at a point relatively close to the top, the partition being provided with an upturned flange fitted within and secured to the inner face of the body portion and extending up to the upper edge thereof to stiffen and 20 reinforce the upper edge with which the cover flange engages.

3. A canister including a body portion, a readily removable cover, a bottom, and an intermediate partition having an outline of 25 weakened material adapted to be easily cut for the purpose of rendering the contents available, said outline having a straight edge adapted for leveling a measuring spoon.

4. A canister comprising a frusto-conical 30 body portion adapted to rest on its larger end and to be filled through said end when in an inverted position, a bottom secured to the body portion adjacent the larger end of the latter, a partition within the body portion 35 providing upper and lower chambers, said partition intimately fitting the adjacent zone of the body portion whereby it is impassable through the smaller end of the body portion during filling of the latter.

40 5. A canister comprising a frusto-conical body portion adapted to rest on its larger end and to be filled through said end when in an inverted position, a bottom secured to the body portion adjacent the larger end of the latter, a partition within the body portion 45 providing upper and lower chambers, said partition intimately fitting the adjacent zone of the body portion whereby it is impassable through the smaller end of the body portion 50 during filling of the latter, and a cover in telescopic engagement with the smaller end of the body.

6. A canister comprising a frusto-conical 55 body portion of paper stock adapted to rest on its larger end and to be filled through said end when in an inverted position, a bottom of paper stock secured to the body portion adjacent the larger end of the latter, a partition 60 of paper stock within the body portion providing upper and lower chambers, and a wall extending from said partition toward the upper end of the body portion, said wall intimately fitting and being secured to the 65 adjacent zone of the body portion, whereby

it is impassable through the smaller end of the body portion during filling of the latter.

7. A canister comprising a frusto-conical body portion of paper stock adapted to rest on its larger end and to be filled through said end when in an inverted position, a bottom of paper stock secured to the body portion adjacent the larger end of the latter, a partition of paper stock within the body portion 70 providing upper and lower chambers, and a wall extending from said partition toward the upper end of the body portion, said wall intimately fitting and being secured to the adjacent zone of the body portion, whereby it is impassable through the smaller end of the body portion during filling of the latter, and a cover telescoped over the smaller end of the body, said cover being of relatively rigid material and being outwardly bulged so that the canister can not be supported with the cover 75 lowermost.
